UNITED STATES PATENT OFFICE

WILLIAM D. SAUNDERS, OF BLACKSBURG, VIRGINIA

LIQUID STRAINER

Application filed May 26, 1932. Serial No. 613,725.

This invention relates to strainers for separating liquids from solids.

An object of the invention is to provide a strainer with a double straining means, that is, the liquids or other materials being separated are made to pass through two straining members instead of just one, thereby insuring a more complete straining action.

Another object of the invention is to provide a device in which the liquid or other material being strained is forced to pass upwardly through one of the straining elements, this upward movement of the liquid greatly facilitating the straining action.

15 The device is preferably used for straining milk and separating the impurities therefrom, but is adapted to be used in connection with other liquids desired to be strained in which different weights or densities are present. It can also be used for extracting foreign matter from liquids.

In the drawing Fig. 1 is a sectional view of the strainer. Fig. 2 is a top plan view with parts broken away.

25 Referring to the drawing 6 indicates a milk can upon which the strainer may be mounted. 7 is a hopper shaped vessel preferably made of metal the upper end of which is open to receive the liquid being strained and the bottom 7a of which is provided with a central restricted neck portion 8 adapted to deliver the strained liquid to a receptacle. Within the neck 8 is removably mounted a tubular member 9 having a bead 10 resting on the top 35 of the neck 8 to support the straining elements above the level of the bottom of the hopper. The member 9 is provided at its upper end with a rim or bead 11, and with a horizontally extending flange 12 having recesses or openings 13 therein, said openings being covered by a straining material, and the rim of the flange 12 is bent down at right angles as at 15.

A straining cloth 16 extends across and is 45 fastened to the top of the member 9 as by a clamping ring 17 and clamped in place around the rim 11 of the member by drawing the ends of the ring together by the screw 18. This cloth extends outwardly over the flange 50 12 and covers the openings therein and the

outer edge of the cloth is clamped between the flange 15 and the side wall 19 of a bell shaped cover 20, as indicated at 21, and the cover also has an internal rib 22 which is pressed down upon the cloth at the angle. 55 The cover has a handle 23 by means of which it may be removed, to uncover and release the strainer cloth.

By the means described the strainer cloth may be tightly clamped upon the top of the tube 9 and also clamped to the flange 15 by forcing the cover down. By removing the cover and the clamping ring the cloth may be removed for washing.

The upper end of the neck 8 extends slightly above the bottom 7a of the hopper, thereby forming a well for the collection of dirt and settling heavier than milk and which do not pass through the cloth.

The hopper may have a dished top 24 with a central opening 25, which will prevent splash when milk is poured in and which will also form a space under the outer part of the top for the collection of floating material carried out toward the outer wall of the hopper. Also, the projection of the rim 11 above the level of the flange 12 forms a sort of well in which any material which for any reason may have passed upwardly through the strainer cloth, with a specific gravity greater than the milk, would be caught or collected, while the milk would rise and flow over the rim and down through the tube 9.

In use, the milk or other liquid to be strained is poured through the opening in the top 24 into the hopper, in quantity sufficient to rise above the level of the cover 20, and rises slowly through the holes 13 and the cloth covering the same. Thence it flows downwardly through the cloth into the central tube 9 and out through the neck 8. It will be seen that the liquid is strained twice, once upwardly and then downwardly through the cloth.

The parts can be easily separated and cleaned, and this is important. The cover 20, tube 9 and parts connected thereto can be lifted out of the hopper. Then the cover 20 can be pulled off and the ring 17 removed to release the cloth and the separated parts 100

washed or sterilized. The heavy sediment collecting on the bottom 7a does not clog the cloth, and the device has other advantages which will be apparent to those skilled in the art.

I claim:

1. A strainer comprising a hopper having an opening in the bottom, a tubular member fitting in said opening and having a perforated flange spaced above the bottom of the hopper, a strainer cloth extending over and secured to the top of the tubular member and covering said flange, and a cover enclosing said member and flange and clamping the edge of the cloth around the outer edge of the flange.
2. A strainer as in claim 1, the bottom of the hopper being below the upper edge of the tubular member.
3. A strainer as in claim 1, the bottom of the hopper having a neck depending from said opening and into which neck the lower end of the tubular member extends.
4. A strainer as in claim 1, the bottom having an outlet neck and the tubular member having an external projection which rests on the upper end of the neck and supports said member with its flange spaced above said bottom.
5. A strainer as in claim 1, and a ring clamping the cloth upon the upper end of said tubular member.
6. A strainer comprising a hopper having an outlet neck at the bottom, a tubular member fitting at its lower end in said neck and having an outwardly projecting flange provided with holes and spaced from the bottom and sides of the hopper, a strainer fabric extending across the top of said member and covering the holes in said flange, means to clamp the fabric around the upper end of said member, and a bell-shaped cover extending over said fabric and fitting and clamping the edge of the same against the outer rim of the flange.

In testimony whereof, I affix my signature.

WILLIAM D. SAUNDERS.
